United States Patent Office

Des. 229,789

Patented Jan. 1, 1974

229,789

FILTERED CIGARETTE

Richard M. Berger, Richmond, Va., assignor to American Filtrona Corporation, Richmond, Va.

Original design application June 21, 1971, Ser. No. 155,371. Divided and this application Apr. 11, 1973, Ser. No. 350,022

Term of patent 14 years

Int. Cl. D27—01

U.S. Cl. D85—6 B

FIG. 1

FIG. 2

FIG. 3

FIG. 1 is a perspective view of a filtered cigarette showing my new design;

FIG. 2 is an elevational view of the tobacco end thereof; and

FIG. 3 is an enlarged elevational view of the filter end thereof.

This application is a division of design application Ser. No. D. 155,371, filed June 21, 1971.

I claim:

The ornamental design for a filtered cigarette, substantially as shown.
